UNITED STATES PATENT OFFICE.

HARRY F. WOERNLEY, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

AUTOMATIC CAR-COUPLING.

1,286,475.

Specification of Letters Patent.

Patented Dec. 3, 1918.

Application filed September 21, 1917. Serial No. 192,550.

To all whom it may concern:

Be it known that I, HARRY F. WOERNLEY, a citizen of the United States, residing at Pittsburgh, in the county of Allegheny and 5 State of Pennsylvania, have invented new and useful Improvements in Automatic Car-Couplings, of which the following is a specification.

This invention relates to couplers, and 10 more particularly to that type having means for locking the coupler heads in tight engagement.

In the above type of coupler, a locking device is provided and a hand operated lever is 15 employed to shift the locking device to its unlocked position when it is desired to uncouple the cars.

After the cars are separated, or before the cars are again coupled up, the locking device 20 should be shifted to its normal locking or coupling position, as otherwise the coupling head will not be locked with the counterpart head when the cars are brought together.

It sometimes happens that the operator 25 fails to shift the locking device to its normal coupling position before coupling up and as a consequence the coupler heads will not be properly locked together.

The principal object of my invention is to 30 provide improved means for automatically insuring that the locking device will be in its coupling position when the cars are coupled up.

In the accompanying drawing; Figure 1 35 is a horizontal sectional view of a coupler head embodying my invention, and showing the parts in the normal coupling position; Fig. 2 a vertical section of the coupler head; Fig. 3 a horizontal section of the coupler 40 head, showing the nose portion of a counterpart head in coupled position and the locking device thrown to its uncoupling position; and Fig. 4 a similar view, showing the parts after a partial separation of the coupler heads has taken place.

As shown in the drawing, the coupler head 45 may be formed of a casting 1 having a projecting portion 2 and a recess 3 for engaging corresponding parts of a counterpart coupler head.

Centrally arranged, transversely of the coupler head, is a vertical and longitudinal plane surface 4 through which one or more openings may be made for fluid pressure 55 communications.

Above and below this plane surface are formed transverse projections or hooked portions 5 having inclined surfaces adapted to engage and interlock with corresponding portions on a counterpart coupler head, each head being provided with a pivoted latch or locking lever 6 having a cam surface for engaging a corresponding curved surface on the projecting portion 2 of the counterpart coupler head, and a spring 7 acting through the medium of a rod 8, pivoted to the lever 6, to force the lever into its locking position.

Secured to the rod 8 is a forked cross head 9 having a central recess containing a pivoted roller 10.

Adjacent to the roller 10 is a double cam 11, mounted on the squared portion of an operating shaft 12 and a handle 13, mounted outside of the casting 1, is provided for operating the shaft 12.

The double cam 11 consists of two diverging projecting portions with an intermediate recess and when the roller 10 rests in the recess, the spring 7 acts on the rod 8 to shift the locking lever 6 to its locking position. Upon shifting the handle 13 in either direction, the roller 10 is forced outwardly by engagement with the surface of one of the projecting portions of the double cam 11 and the locking lever 6 is then shifted to its unlocked position.

According to the present invention, there is provided a toggle lever device comprising a lever 14 pivotally mounted on the pivot pin 15 of rod 8 and a lever 16 pivoted to lever 14 at one end and working on a fixed pivot pin 17 at the opposite end. The lever 16 carries a trip projection 18 adapted to be thrown into the path of the projection 2 of the counterpart coupler head when the locking lever is moved to the uncoupling position.

In operation, the coupler heads are locked together in the usual way, the projection 2 of one head engaging in the recess 3 of the other head and when the heads are in the coupled position, the locking levers 6, which were pushed aside as the coupler heads moved into engagement, are thrown back to locking position, so as to tightly lock the coupler heads together.

If it is desired to uncouple the heads, the handle 13 is shifted to the uncoupling position, so that the locking lever 6 of each head is moved out of engagement with the projection 2 of the other head and this permits

the coupler heads to separate when the cars are pulled apart. The uncoupling movement of the locking lever 6 also shifts the toggle levers 14 and 16 so that they assume substantial alinement, as shown in Fig. 3 of the drawing, and in this position of the levers, the rod 8 is locked against return movement.

The tripping projection 18, however, is brought by this movement into the path of the projection 2 of the counterpart coupler head, so that as the coupler heads are pulled apart, the projection 2 will engage the member 18, as shown in Fig. 4 of the drawing, and upon movement of the same a certain distance, the toggle levers 14 and 16 assume relative angular positions, such that the spring 7 is able to act on the locking lever and then throw the parts to the normal coupling position, as shown in Fig. 1 of the drawing.

It will now be evident that the act of separating the coupler heads, automatically returns the parts to the normal coupling position, ready for again coupling up, without any action on the part of the operator.

It should also be noted that if, for any reason, the handle is turned to the uncoupling position while the car is separated, the parts of the coupler will be automatically returned to the coupling position when the counterpart couplers are brought together, since the projection 18 will be shifted by the movement of the projection 2 into the corresponding recess 3 of the counterpart coupler, as in the case of uncoupling.

Having now described my invention, what I claim as new and desire to secure by Letters Patent, is:—

1. An automatic coupler comprising a member having a projecting hooked portion adapted to engage a similar portion of a counterpart coupler, a locking lever for clamping said members together, a spring tending to move said lever to its locking position, a pair of pivotally connected arms fulcrumed at one free end and pivotally connected to the lever at the other free end.

movement of the lever to uncoupling position being adapted to move said arms, so that the connecting joint is brought into alinement with the fulcrum point and the pivotal connection, thereby forming a lock to prevent the return movement of the lever.

2. An automatic coupler comprising a member having a projecting hooked portion adapted to engage a similar portion of a counterpart coupler, a locking lever for clamping said members together, a spring tending to move said lever to its locking position, a pair of pivotally connected arms fulcrumed at one free end and pivotally connected to the lever at the other free end, movement of the lever to uncoupling position being adapted to move said arms, so that the connecting joint is brought into alinement with the fulcrum point and the pivotal connection, thereby forming a lock to prevent the return movement of the lever, and a tripping member carried by said toggle lever device and operated upon separation of the coupler heads for tripping the toggle lever device to permit movement of the locking lever to the normal coupling position.

3. An automatic coupler comprising a member having a projecting hooked portion adapted to engage a similar portion of a counterpart coupler, a locking lever for clamping said members together, a spring tending to move said lever to its locking position, a toggle lever device comprising pivotally connected levers adapted to be moved to substantial alinement by the uncoupling movement of the locking lever, to thereby hold the locking lever in its uncoupling position, and a projection carried by one of the toggle levers and operated by the separation of the coupler heads for throwing the toggle levers out of alinement, so as to permit movement of the locking lever to its coupling position.

In testimony whereof I have hereunto set my hand.

HARRY F. WOERNLEY.
